UNITED STATES PATENT OFFICE.

FREDERICK DIEHL, OF ELIZABETH, NEW JERSEY, ASSIGNOR TO DIEHL MANUFACTURING COMPANY, OF ELIZABETH, NEW JERSEY, A CORPORATION OF NEW JERSEY.

SEWING-MACHINE-MOTOR BRACKET.

Application filed May 6, 1922. Serial No. 552,109.

To all whom it may concern:

Be it known that I, FREDERICK DIEHL, a citizen of the United States, residing at Elizabeth, in the county of Union and State 5 of New Jersey, have invented certain new and useful Improvements in Sewing-Machine-Motor Brackets, of which the following is a specification, reference being had therein to the accompanying drawings.

10 This invention relates to sewing machine motor attachments of the type adapted to be mounted on a sewing machine gooseneck in driving relation with the sewing machine shaft, and has for an object to provide an 15 attachment of this type with means whereby the usual bobbin-winder customarily associated with the machine may be driven.

In certain types of sewing machines the bobbin-winder is mounted on the front side 20 of the standard or vertical member of the gooseneck in proximity to the sewing machine balance-wheel so that the bobbin-winder may be pressed against the periphery of the balance-wheel for reception of 25 the power necessary to drive it. In other machines in which there is a forwardly projecting feed-regulating lever mounted on the standard adjacent the balance-wheel and immediately below the main-shaft, the 30 bobbin-winder cannot be mounted on the standard to engage the balance-wheel without interfering with the feed-regulating lever. The bobbin-winder, in such cases, is mounted at a level below the feed-regulating 35 lever and preferably on the sewing machine bed-plate where it may be pressed into contact with the forward limb of the driving belt customarily used in a treadle-driven outfit.

40 In a motor driven outfit the absence of a treadle-driven belt deprives the bobbin-winder of its customary driving means and the problem of driving it from a motor-attachment is presented.

45 To the attainment of the ends in view there is provided a two-armed bracket adapted to be secured at the juncture of its arms to the usual seat provided at the balance-wheel side of the vertical member of 50 the gooseneck. One arm of the bracket extends rearwardly and supports the driving motor which may be belted to a pulley on the sewing machine shaft. The other arm of the bracket is extended forwardly and 55 carries a pulley-wheel which is located in

proximity to the bobbin-winder so that the latter may be pressed into engagement with the periphery of such pulley wheel which is belted to the motor. The distance of the bobbin-winder pulley from the motor-pulley 60 may be such that a driving belt of standard length such as is used for connecting the motor to the sewing machine shaft can be used to connect the motor to the bobbin-winder driving pulley. 65

In the accompanying drawings Fig. 1 is a side elevation of the attachment as applied to a sewing machine. Fig. 2 is a top plan view of the same; the standard or vertical member of the gooseneck being shown in section, and Fig. 3 is a view showing modification of the invention. 70

In the preferred embodiment of the invention, as illustrated, 1 represents the sewing machine bed from which rises the standard 2 or vertical member of the gooseneck in which is journaled the main-shaft 3 carrying the balance-wheel 4; the latter being commonly formed with a hub grooved at 5 to receive a driving belt. The particular 80 machine chosen has the usual forwardly extending feed-regulating lever 6 and is formed with the usual attachment seat 7. 75

Mounted preferably on the bed 1 of the machine is the usual bobbin-winder which 85 commonly comprises the spindle 8, one end of which is reduced at 9 to receive the bobbin 10 to be wound. The other end of the spindle 8 carries the grooved pulley 11. The spindle 8 is journaled in the spring-pressed 90 rocking frame 12 which is pivoted at 13 to the base-member 14 adjustably secured to the sewing machine bed 1 by the screw and slot connection 15. A spring 16 tends to swing the frame 12 forwardly about its 95 pivot 13. The frame 12 is held in rearwardly displaced or driving position by means of the latch 17 which engages the shoulder 18 on the frame 12. The latch 17 is fixed to a shaft 19 to which is also fixed 100 a feeler 20 adapted to pass between the cheek-pieces of the bobbin being wound. When the frame 12 is pressed rearwardly the latch 17 moves under the shoulder 18 and holds the frame in winding position 105 with the grooved pulley pressed against the usual belt heretofore used to connect the pulley 5 with the usual treadle-operated wheel beneath the bed 1. As the bobbin 110 fills with thread the feeler 20 is displaced

2
forwardly until, when the bobbin is full, the latch 17 is carried forwardly sufficiently to release the frame 12 which is thereupon shifted forwardly about the pivot 13 by the 5 spring 16 to interrupt the driving relation between the pulley 11 and the belt.

In accordance with the present improvement the machine is driven by a suitable electric motor 21 having preferably a doubly grooved pulley 22 connected by a belt 23 of standard length to the pulley 5. The motor is preferably secured by screws 24 and a rib-and-groove connection 25 to the inclined end 26 of one arm 27 of a bracket 28 adapted 10 to be secured by a screw 29 to the seat 7 previously referred to; such seat 7 being customarily provided on the standards of sewing machines of various well known types. The inclination of the arm 26 and rib 25 is 15 preferably such that it is perpendicular to a line joining the centers of the pulleys 5 and 22, whereby adjustment of the motor along the arm 26 may be effected without appreciably altering the belt length, as disclosed 20 in the application of Martin Hemleb, Serial No. 383,708, filed May 24, 1920.

The bracket 28 is formed with a forwardly extending arm 30 at the end of which a pulley 31 is mounted by means of a bearing screw 32. The pulley 31 is preferably formed with a belt groove 33 and driving surface 34 against which may be pressed the rubber ring 35 fitted to the pulley 11 of the bobbin-winder. The distance between the 30 centers of the pulleys 22 and 31 is such that the sewing machine driving belt 23 or another belt of standard length may be used.

The pulley 11 may have the friction ring 35 omitted and may be arranged to bear directly upon the belt 23, as shown in Fig. 3.

Having thus set forth the nature of the invention, what I claim herein is:—

1. A sewing machine driving attachment comprising a bracket adapted to be secured 45 to the usual attachment seat on the gooseneck of a sewing machine, and a sewing machine driving motor and bobbin-winder pulley mounted in spaced relation on said bracket and adapted to be connected together 50 for transmission of power from said motor to said pulley.

2. A sewing machine driving attachment

comprising a bracket adapted to be secured to the gooseneck of a sewing machine and having oppositely extending arms, a driving motor mounted on one of said arms, and a bobbin-winder pulley mounted on the other of said arms and adapted to be belted to said motor.

3. A sewing machine driving attachment 60 comprising a bracket adapted to be secured to the gooseneck of a sewing machine, a driving motor and a bobbin-winder pulley mounted in spaced relation on said bracket and adapted to be connected together by a belt, 65 said bobbin-winder pulley having a belt-groove and a driving surface into frictional engagement with which a bobbin-winder may be pressed.

4. The combination of a sewing machine 70 outfit including a frame, a sewing machine pulley and a bobbin-winder pulley, of a bracket secured to said frame, a motor mounted on said bracket and having a shaft and driving pulley, a belt connecting the 75 motor and machine, and a pulley mounted on said bracket in spaced relation to said motor and adjacent the bobbin-winder.

5. The combination of a sewing machine outfit including a frame, a sewing machine 80 pulley and a bobbin-winder pulley, of a bracket secured to said frame, a motor mounted on said bracket and having a shaft and driving pulley, a belt connecting the 85 motor and machine, and a pulley mounted on said bracket adjacent the bobbin-winder, the distance between the centers of the last mentioned pulley and the motor-shaft being such that a belt of standard length such as used 90 for driving the sewing machine can be used for winding bobbins.

6. The combination with a sewing machine having a bed, gooseneck, main-shaft pulley, and bobbin-winder mounted on said bed adjacent the base of the gooseneck, of a 95 bracket mounted on said gooseneck, a motor mounted on said bracket, a belt connecting the motor and mainshaft pulley, and a bobbin-winder driving pulley mounted on said bracket in spaced relation to the motor-pulley and adapted to be belted to said motor.

In testimony whereof, I have signed my name to this specification.

FREDERICK DIEHL.
